UNITED STATES PATENT OFFICE.

LEVI C. STRONG, OF GREENFIELD, MASSACHUSETTS, ASSIGNOR TO THE
ALBANY AGRICULTURAL COMPANY, OF ALBANY, NEW YORK.

ANIMAL-POWER.

SPECIFICATION forming part of Letters Patent No. 291,640, dated January 8, 1884.

Application filed November 24, 1883. (No model.)

To all whom it may concern:

Be it known that I, LEVI C. STRONG, a citizen of the United States, residing at Greenfield, in the county of Franklin and State of Massachusetts, have invented certain new and useful Improvements in Animal-Powers, (for which I filed a previous application July 11, 1881,) of which the following is a specification, reference being had therein to the accompanying drawings, in which—

Figure 1 is a perspective of an animal-power constructed in accordance with my invention, and Fig. 2 is a detail, hereinafter described.

Like letters refer to like parts in both figures.

This invention relates to that class of machines known as horse-powers or animal-powers, and to that portion of such class which involves an endless tread, upon which a horse, dog, sheep, or other animal walks, and thus gives motion to the endless tread, which motion is conveyed by suitable means to any desired mechanism for the operation thereof.

The novel features of the machine herein described and shown will be specifically set forth in the claims.

In the drawings, A represents a main framework, provided at its front end with suitable boxes or bearings, B, for the shaft of any ordinary and suitable driving-pulleys, C, which support and are driven by the endless tread D. To said shaft is rigidly secured a crank, E, slotted for the adjustable connection therewith of a pitman, F, which at its opposite end is pivotally secured to the vibrating bar or lever G.

As thus far described the parts mentioned—that is to say, the main frame, driving-pulleys, crank, and pitman—may be of any ordinary construction.

The following pulleys C and the supporting-pulleys C² are supported or journaled in a secondary frame, H, connected at its front end pivotally—in this instance by brackets h—to the front end of the main frame A, and at its rear end by a cam or cams, I, secured to a shaft, J, which is provided with a rigidly-mounted arm or lever, K, which traverses a sector, L, secured to the main frame, said shaft

J also being suitably journaled in said main frame, whereby the cam or cams I, being in direct contact with the side rails of the secondary frame, serve as its sole support at the rear end thereof, and as means which permit and enable an adjustment of said rear end to produce any desired inclination of the endless tread, and by means of the cam or cams, lever, and sector the secondary frame is firmly locked in desired positions.

The endless tread D (shown in part by dotted lines, Fig. 1) is composed of lags d d (see Fig. 2, which is an inverted plan or bottom view) and links M M'. Each of the links comprises a web or strap, m, having hinge-lugs m', and projecting stops m², having lateral or inwardly-projecting ledges or clamping-jaws m³. The hinge-lugs m' of the link M are provided with pintles m⁴, while those of the link M' are bored to receive pintles, and the web of the former link is provided with points or spurs m⁵, while the web of the latter is recessed or bored for a screw or bolt, as m⁶.

The lags and links are put together in the following manner: The link M is driven on the end of one lag until it is flush. The link M' is in like manner put upon a second lag, the pintle of the first link entering the hinge-lug of the second, when the screw of bolt m⁶ is driven into the second lag. It will now be seen that the points or spurs of the link M will prevent either link from moving inward upon the lags, and that the screw m⁶ prevents either link from moving outward thereupon by reason of the spurs, the screw or bolt, and the hinge-joint between the two links. Duplicating this construction at each end of the lags and employing suitably flanged and sprocketed driving and following pulleys, it will be seen that cheapness, strength, and serviceability are secured in the endless tread. The vibrating bar or lever G is adapted at its free end g for connection with desired machinery, as heretofore; but the opposite end of said bar or lever is not, as heretofore, pivoted directly to the main frame, the object being to avoid and overcome the movement in a curved path of said free end of the bar. The pitman F is pivotally connected to the bar at f. The rear end of the

bar is supported by a link, N, pivotally secured to the bar, and above it to the main frame—in this instance by a bracket, n.

Between the pitman F and the link N is a 5 second link, O, pivoted to the bar, and below it to the main frame at p.

By the employment of the links N and O, relatively arranged as shown, when the crank E is moved upward to its full throw, the pitman raises the free end of the bar, the link O raises and carries forward the middle portion thereof, while the link N carries the rear end thereof slightly downward and forward, so that the resultant vertical movement of the free 15 end is in a substantially straight line.

As before stated, the main frame may be of any desired well-known construction, and so, also, any part or combination of parts may be changed in construction, proportion, and relative arrangement to any extent within the skill 20 of persons conversant in the construction of this class of machinery, and I therefore do not limit myself to the exact details herein shown and described.

Having described my invention and its operation, what I claim as new is—

1. In an animal-power, the combination of a main frame supporting a driving-pulley, a secondary frame supporting a following pulley, an endless tread, and a cam or cams journaled in the main frame and bearing directly 30 upon or against said secondary frame, substantially as specified.

2. The vibrating bar of an animal-power, connected by suitable means to the crank of a driving-pulley, in combination with two links pivotally connected to said bar and to the main frame, one of said links being pivoted to said

frame above and the other below said bar, substantially as specified.

3. The combination of a series of lags with a series of links alternately provided with webs having spurs and hinge-lugs, and with webs having similar hinge-lugs and a screw hole or recess, substantially as specified.

4. The combination of the bar G and the links N O, the frame A, pitman F, and a driving-pulley having a crank, E, substantially as specified.

5. The combination of the endless tread D, 5C pulley C, crank E, pitman F, bar G, supported by the hanging link N, and the link O, substantially as specified.

6. The combination of the main frame A, the secondary frame H, pivoted to the main frame, and carrying the following pulley C', with the shaft J, cam I, arm K, and sector L, substantially as specified.

7. A lag-link comprising the spurred or recessed web m, the stops m², jaws m³, and hinge-lugs m', substantially as specified.

8. The combination of a lag-link, as M, having spurs or points, as m⁵, with a lag-link, as M', provided with a bored or recessed web, substantially as specified.

9. The combination of the lags d d with the links M M', having hinge-lugs m', stops m², jaws m³, and pintles m⁴, substantially as specified.

In testimony whereof I affix my signature in presence of two witnesses.

LEVI C. STRONG.
